DESIGN FOR A COMPACT

William M. Emery, Shaker Heights, Ohio

Application March 2, 1944, Serial No. 112,767

Term of patent 14 years

(Cl. D86—10)

To all whom it may concern:

Be it known that I, William M. Emery, a citizen of the United States and a resident of Shaker Heights, in the county of Cuyahoga and State of Ohio, have invented a new, original, and ornamental Design for Compacts, of which the following is a specification, reference being made to the accompanying drawing, constituting a part thereof.

Figure 1 is a view in side elevation of a compact showing my new design;

Figure 2 is a perspective view of the under side of Figure 1.

I claim:

The ornamental design for a compact, substantially as shown.

WILLIAM M. EMERY.
